W. S. RAWSON.
FOLDING TOP FOR VEHICLES.
APPLICATION FILED OCT. 22, 1917.

1,347,554.

Patented July 27, 1920.

Inventor:
William S. Rawson,
by Henry Bent, James Murray,
Attys.

UNITED STATES PATENT OFFICE.

WILLIAM S. RAWSON, OF BRIDGEPORT, CONNECTICUT.

FOLDING TOP FOR VEHICLES.

1,347,554.

Specification of Letters Patent. Patented July 27, 1920.

Application filed October 22, 1917. Serial No. 197,783.

To all whom it may concern:

Be it known that I, WILLIAM S. RAWSON, a citizen of the United States, and a resident of Bridgeport, county of Fairfield, and 5 State of Connecticut, have invented an Improvement in Folding Tops for Vehicles, of which the following description, in connection with the accompanying drawings, is a specification, like characters on the drawings 10 representing like parts.

This invention relates to folding tops for vehicles, and is more especially concerned with a bow-holder for holding the bows of the top in place when the latter is folded. 15 My invention will be best understood by reference to the following description when taken in connection with the accompanying drawings of one specific embodiment thereof, while its scope will be more particularly pointed out in the appended claims.

In the drawings:

Figure 1 is a side elevation of a portion of a vehicle top having a bow-holder embodying my invention; and

25 Fig. 2 is a sectional view on line 2—2 of Fig. 1.

Referring to the drawings, and to the embodiment of my invention which is illustrated therein, I have shown a portion of a vehicle top comprising a plurality of bows 3, 4, 5 and 6, the latter resting on a bow support 7, which may be of any suitable form but is herein provided with a channel or groove 8, suitably shaped to receive the lowest bow 6. This bow support is herein provided with an ear 9, apertured to receive a top iron 10, which is secured therein by a set-screw 11. The bows may be spaced apart by any suitable means, herein a set of bow spacers 12, 13 and 14, interposed between the bows and adapted to hold the latter suitably spaced apart, as well as against lateral displacement.

As a means for urging the bows toward the bow support, and holding them firmly but with somewhat yielding pressure, I have provided two oppositely facing hooks 15 and 16, the upper hook engaging the uppermost bow and the lower hook engaging the bow support, while suitable resilient means, herein in the form of a spring 17, is suitably connected to said hooks to draw them toward each other, thereby to urge the bows toward the bow support. This spring may be otherwise appropriately connected to the hooks, but in the present example the latter are

formed on two telescopically arranged members 18 and 19, respectively. The member 18 is provided with a cylindrical bore 20 to receive the spring 17, the latter abutting at one end against a movable abutment 21 carried by the member 19, and the other end against a fixed abutment 22 threaded into the member 18. 60

The upper hook 15 may be, and is herein provided with a suitable cushion 23, preferably formed of rubber or similar yielding material, having a shank or stem 24 extending through an aperture in the hook 15, whereby the cushion is attached to and held 70 in its proper relation with the hook at all times. The lower hook 16 in the present example enters an opening 25 in the bow support 7, thus interlocking with the latter and being held against accidental displacement. 75

As a means for enabling the bow-holder to be temporarily elongated in attaching it to or detaching it from the bows and bow-holder, I have herein provided a suitable handle 26 having two laterally projecting portions 27, upon which the fingers may be placed, thereby to exert a downward pull on the member 19 to compress the spring and to enable the hook 16 to be engaged with or disengaged from the opening 25 at will. 80 The bow-holder is applied to the bows by first hooking the upper hook 15 over the uppermost bow 3, then grasping the handle 26 and exerting a downward pull thereon, thereby to elongate the holder, next placing the lower hook 16 in proper registration with the opening 25, and finally releasing the handle thereby to permit the lower hook to enter its aperture under the influence of 85 the spring. When once the holder is applied, it retains the bows securely, yet with somewhat yielding pressure. It may be instantly removed by a reversal of the foregoing operating, and when removed may be 90 stored in any convenient place about the vehicle, thus leaving the other parts of the top free from encumbrance. 95

While I have herein shown and described one specific form or embodiment of my invention for illustrative purposes, and have disclosed and discussed in detail the construction and arrangement incidental to one specific application thereof, it is to be understood that the invention is limited neither 105 to the mere details or relative arrangement of parts, nor to its specific embodiment here- 110

in shown, but that extensive deviations from the illustrated form or embodiment of the invention may be made, without departing from the principles thereof.

5 Having thus described my invention, what I claim and desire by Letters Patent to secure is:—

1. In a folding top for vehicles, the combination of a set of bows, a bow-support 10 provided with a depression to receive the lowermost bow and having a lateral projection provided with an opening at one side of said depression, two telescopically arranged members one of which is hollow and 15 the other working therein, said members being provided with oppositely facing hooks, one of which engages the uppermost bow and the other of which enters said opening and engages said bow-support, and one 20 of said members being provided with a handle for relatively extending said members, and a spring located within one of said members and tending to collapse said mem-

bers and to draw said hooks toward each other thereby to urge said bows toward said support. 25

2. In a folding top for vehicles, the combination of a set of bows, a bow-support provided with a depression to receive the lowermost bow and provided also with an 30 opening at one side of said depression, a pair of oppositely facing hooks, one engaging the uppermost bow and the other entering said opening and engaging said bow-support, two collapsibly connected members 35 carrying said hooks, respectively, one of said members being provided with a handle having a pair of laterally projecting portions, and a spring connected to said members and tending to draw said hooks toward 40 each other thereby to urge said bows toward said support.

In testimony whereof, I have signed my name to this specification.

WILLIAM S. RAWSON.
